TREE PRUNING SAW

Ronald E. Hyskell, Seattle, Wash., assignor to Husky Manufacturing, Inc., Seattle, Wash., a corporation of Washington

Filed Apr. 18, 1960, Ser. No. 60,227

Term of patent 14 years

(Cl. D40—1)

FIGURE 1 is a top perspective view of the tree pruning saw showing my new design;

FIGURE 2 is a side elevational view thereof, a portion of the shaft being broken away for convenience of illustration;

FIGURE 3 is an elevational view of one end thereof taken from the right of FIG. 2; and

FIGURE 4 is an elevational view of the opposite end thereof.

The dominant features of my design reside in the following portions of the drawing.

I claim:

The ornamental design for a tree pruning saw, substantially as shown and described.
